UNITED STATES PATENT OFFICE.

JOHN F. MONNOT, OF NEW YORK, N. Y., ASSIGNOR TO DUPLEX METALS COMPANY, OF NEW YORK, N. Y., A CORPORATION OF NEW YORK.

APPARATUS FOR PRODUCING COMPOUND METAL BODIES.

No. 878,984.

Specification of Letters Patent.

Patented Feb. 11, 1908.

Application filed November 17, 1906. Serial No. 343,810.

To all whom it may concern:

Be it known that I, JOHN F. MONNOT, a citizen of the United States, residing at New York, in the county of New York and State 5 of New York, have invented certain new and useful Apparatus for Producing Compound Metal Bodies; and I do hereby declare the following to be a full, clear, and exact description of the same, such as will enable 10 others skilled in the art to which it appertains to make and use the same.

My invention relates to apparatus for producing compound metal bodies, and embodies improvements in the apparatus illustrated and described in my Letters Patent dated April 30, 1907, No. 851,993; the apparatus illustrated and described in my application for Letters Patent filed April 10th, 1906, Sr. No. 310,910, and in the 15 apparatus illustrated and described in my application for Letters Patent filed July 31st, 1906, Sr. No. 328,606. My said apparatus is particularly adapted for carrying out the processes set forth in my Letters Patent 20 No. 851,684, dated April 30, 1907 and No. 853,716, dated May 14, 1907.

According to the process of said Patent No. 851,684 a metal ingot or other article to be coated, is immersed in a bath of molten 25 coating metal and then by means of a suitable casing or chamber, which is caused to surround said core while the latter is still in the bath of coating metal, a layer of said coating metal of suitable thickness is segregated from the main body of such metal, the 30 said casing or chamber, with the article to be coated and the enveloping layer of molten coating metal therearound, being then removed from the bath of coating metal, and said segregated layer of coating metal being 35 then allowed to solidify on the article to be coated, after which the enveloping casing or chamber is removed. This process is known as the "segregation process".

The process of my said Patent No. 853,716, 40 is intended for uniting unlike metals which do not weld together readily, particularly when the coating metal has a lower melting 45 temperature than the metal to which the coating is to be applied. According to said process, the article to be coated is immersed in a bath of molten coating metal maintained at such a temperature that the molten metal is in what is known as a "supermolten" condition; a condition characterized by extreme

fluidity and apparently by a considerable degree of chemical activity. The supermolten metal unites with the surface of the article to be coated. Sometimes the entire coating to be applied to said article is formed 50 thereon at one time, by segregating from the molten metal of the supermolten bath a layer of the molten metal surrounding said article, and permitting the same to solidify against the surface of said article; and sometimes a mere film coating or "alloy-film", as it is called, is formed in the supermolten bath, and then the article to be coated is removed, under conditions precluding oxidation, is immersed in a second bath of coating metal 55 of ordinary casting temperature, and a layer of such molten metal surrounding the film-coated surface is segregated from the main body of coating metal and caused to unite with and solidify against the alloy-filmed 60 surface. In carrying out the said process by segregation apparatus such as described, some difficulty has been experienced in obtaining a perfectly tight joint between the bottom plate and lower edge of the casing. 65 Also some difficulty has been experienced due to the sticking of the bottom plates to the coating metal; the coating metal sometimes adhering so firmly to the bottom plates 70 that they have been broken in detaching them. 75 Since the bottom plates must be made with great accuracy it is desirable that they should separate readily from the ingot.

The objects of my present invention are to 80 form a tight joint between the bottom plate and casing, and to prevent the bottom plate 85 from sticking to the ingot.

A further feature of my invention is an 90 improved form of casing provided with means whereby molten metal may be introduced into the casing from above.

I will now proceed to describe my invention with reference to the accompanying drawing in which coating apparatus comprising two forms of casing embodying my 100 invention are illustrated.

In the said drawing: Figure 1 shows in side view and partly in vertical section, a coating apparatus such as described, comprising a 105 casing, a bottom plate, hoisting apparatus for raising and lowering the casing and bottom plate together or separately as desired, and a truck for moving the apparatus from place to place. Fig. 2 is a similar view of an alternative form of casing provided with 110

means for admitting the molten metal from near the top of the casing.

In the said drawing, 1 designates said casing, 2 the bottom plate, 3 the ingot to be coated, 4 the head of the casing, which also constitutes a weight to insure immersion of the casing in the molten metal, 5 designates a porter bar, 6 a hoisting apparatus suspended from a truck 7 mounted on a rail 8, 10 and 9 another hoisting apparatus suspended from hoist 6 and having the porter bar 5 suspended from it, and having also winding drums upon which are wound cables 10 connected to casing 1. In the construction 15 shown the bottom plate 2 is connected to the ingot 3 itself, by means of a screw 11. Said bottom plate has a raised rib or flange 12 of approximate inverted V-section adapted to fit into a recess 13 of similar shape, in the 20 bottom of the casing.

The casing is provided with a valved pipe 14 by which gas may be supplied to the casing and by which the gas within the casing may be withdrawn when desired. The 25 hoists 6 and 9 illustrated, are electrical hoists, the illustrations being purely diagrammatical and not designating any particular mechanical construction of hoist.

So far as described, the apparatus illustrated is substantially that of my application Ser. No. 328,606, above mentioned. In the use of such apparatus of considerable size, it has been found difficult to so pack the groove 13 in the bottom of the casing, as 30 to insure a perfectly tight joint between the bottom plate and casing. I have found that the material used for packing should be one which, while substantially solid at ordinary temperatures, so that it will not fall out of 35 the recess in the casing, is plastic at the temperature of the molten metal and yet not so liquid at such temperature as to flow out or to permit the molten metal to force itself past. I have found that a suitable packing 40 material for the purpose is formed by fluor-spar. This substance may be run into the recess 13 in molten condition and permitted to solidify, or it may be mixed, in powder or granular condition, with a suitable binder, 45 such as water glass (silicate of an alkali) and thus made plastic, and in such plastic condition placed within the recess 13, the mixture being dried to drive off as much of the 50 water as possible. In either case the packing 55 material so applied becomes sufficiently plastic when the casing is inserted within the molten metal under the influence of the heat of such metal, to receive easily the sharp rib 12 of the bottom plate, and so form a tight 60 joint.

In my Patents Nos. 851,684 and 851,993 both dated April 30th, 1907, I have illustrated forms of segregation apparatus in which the 65 casing is in the bottom plate, the lower

edge of the casing being V-shaped. The plastic packing material described, is of course equally suitable for use in that form of apparatus.

In the apparatus shown in Fig. 2, holes 15 70 are provided in the upper part of the casing through which molten metal may be introduced, and a sliding shield 16 is provided for covering or uncovering said holes at will. In using said form of apparatus, the joint between the bottom plate and casing is formed before introducing the casing to the molten metal. The same packing material as above described, may be used, and may be heated up to soften it to receive the rib of the bottom plate. When introducing the casing into the molten metal, the holes 15 are kept closed until they are close to the surface of the molten metal, and then the shield 16 is raised so that as said holes enter the molten 80 metal the latter will flow into the casing. Suction may be applied by means of pipe 14 to draw out of the casing the gas therein and any gas carried in by the molten metal and also, if desired, to produce a partial vacuum 90 within the casing, so decreasing the hydrostatic pressure on the joint between the bottom plate and casing.

In the drawings I have shown a thin washer 17 between the bottom plate 2 and the ingot 3, the diameter of which washer is substantially the internal diameter of the casing 1. This washer is to prevent the molten metal inclosed within the annular space between the ingot and casing from sticking 100 to the bottom plate. When this washer is used, the molten metal contacts with said washer instead of with the bottom plate directly. Possible adhesion of said washer to the end of the coated billet is immaterial; 105 whereas it is desirable that the bottom plates themselves shall not adhere to the end of the coated billet. Such bottom plates are relatively expensive, owing to the necessity of fitting them to the grooved ends of the casings. 110

What I claim is:—

1. Coating apparatus comprising in combination an open-ended casing for containing fluid metal and an end plate therefor, one of 115 said parts having a recess and the other a rib adapted to enter said recess, and a packing material within said recess, consisting principally of a material which is solid at ordinary temperatures but plastic at the temperature of molten metal.

2. Coating apparatus comprising in combination an open-ended casing for containing fluid metal and an end plate therefor, one of 120 said parts having a recess and the other a rib adapted to enter said recess, and packing material within said recess comprising fluor-spar.

3. Coating apparatus comprising in combination an open-ended casing, an end plate therefor, and a washer covering said end 130

plate, and arranged to extend substantially to the side of the casing when said casing and end plate are together.

4. Coating apparatus comprising in combination an open-ended casing for containing fluid metal and an end plate therefor, said casing provided with a separate opening for the admission of molten metal, with a shield for such opening, and with means for making

a fluid-tight joint with said end plate through 10 the intermediary of plastic packing material.

In testimony whereof I affix my signature, in the presence of two witnesses.

JOHN F. MONNOT.
